(57) **CLAIM**

The ornamental design for a wireless microphone, as shown and described.

DESCRIPTION

FIG. 1 is a front elevational view of a wireless microphone; showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 5 is a bottom plan view thereof.
FIG. 7 is a front and top perspective view thereof; and,
FIG. 8 is a rear and bottom perspective view thereof.
The broken lines in the figures illustrate portions of the article that form no part of the claimed design.
